Patented Mar. 1, 1921.

UNITED STATES PATENT OFFICE.

RALPH A. D. PRESTON, OF AKRON, OHIO, ASSIGNOR TO THE GOODYEAR TIRE & RUBBER COMPANY, OF AKRON, OHIO, A CORPORATION OF OHIO.

DIRIGIBLE.

1,370,043.

Specification of Letters Patent.

Patented Mar. 1, 1921.

Application filed March 11, 1918. Serial No. 221,780.

To all whom it may concern:

Be it known that I, RALPH A. D. PRESTON, a citizen of the United States, residing at Akron, in the county of Summit and 5 State of Ohio, have invented new and useful Improvements in Dirigibles, of which the following is a specification.

My present invention relates to improvements in dirigibles and more particularly to 10 those of the scout type of non-rigid construction.

It has been the custom heretofore, in housing dirigibles, to sacrifice hangar space to accommodate the relatively long stream line 15 structures which are employed for giving more efficient form to the bag and to increase the speed of the dirigible.

This space is expensive to build and maintain and it is therefore the principal object 20 of my invention to substitute for the present pointed tail which is now used for stream line purposes only, an air inflated tail of very light fabric, that may be deflated when the dirigible is housed in the hangar.

Another object is to provide an air inflated tail that can be inflated while underway by the balloonet inflating means, or other means that may be provided therefor. 25

The above and additional objects of a 30 similar nature, which will be hereinafter more specifically treated, may be accomplished by such means as are illustrated in the accompanying drawings, described in the following specification, and then more 35 particularly pointed out in the claims which are appended hereto and form a part of this application.

With reference to the drawing, wherein 40 there has been illustrated a preferred embodiment of the invention as it is reduced to practice, and throughout the several views of which similar reference numbers designate corresponding parts:

Figure 1 is a side elevation of a dirigible 45 of the non-rigid type; and

Fig. 2 is a perspective view of the rear end of the dirigible showing the tail deflated in full lines and inflated in dotted lines.

As previously stated, present day dirigibles of the non-rigid type are usually constructed with a long, pointed tail, which does not in any way effect the factor of safety but serves only for stream line purposes. By my present invention I propose to cut 50 off this tail preferably at about the line 55

A—B in Fig. 1, and to substitute a long, conical shaped tail 10 of very light construction adapted to be air inflated during flight or before flight, by any suitable means, as, for example, connection to the balloonet 60 blower inflation system of the dirigible, (not shown), or by the scoop system now in use in some types of dirigibles and kite balloons.

A valve 11 of any suitable construction is 65 provided for connection to the inflation system or to any suitable blower pump or other air supply, (not shown in the drawings).

It will be understood that a suitable end closure 12 will be employed to effectively 70 seal the end of the gas bag proper to retain the gas within the bag and maintain the required configuration of the bag.

From the foregoing it will be apparent that I have provided an efficient stream line 75 tail that may be deflated to permit the dirigible to be housed in a smaller and more economical hangar. For example, a popular type of dirigible now used and known as "the Navy Scout type" is usually about 121 feet 80 in length over all, of which about twenty-one feet is used for stream line purposes and is not essential to the lift of the dirigible. By using my improved structure, the same dirigible can be housed in a hundred 85 foot hangar, and the costly gas and hangar space, which would otherwise be used, saved.

It will be understood that, although I have described and illustrated one particular design of tail, I do not wish to be limited to that particular design nor to the proportions quoted in the example given. I also wish it to be understood that I may use other means of inflation than those mentioned without departing from the scope of 95 the appended claims.

It is further to be understood that, while in the preferred embodiment of the invention, the deflatable tail is secured in a relatively permanent manner to the gas bag 100 body, the tail may, if desired or deemed expedient, under special conditions, be connected to the body of the gas bag by a means of a nature to permit quick detachment of the tail portion.

It will also be apparent that while in the preferred use of my invention I inflate the tail portion with air, suitable gas may be employed for the same purpose without departing in any way from the spirit or scope 110

of my invention, as defined in the appended claims.

What I claim is:

1. A gas bag for lighter-than-air craft, comprising an inflatable body portion, and a collapsible tail portion connected to the end of said body portion, said tail portion being deflatable and inflatable independently of said body portion.
- 10 2. A gas bag for lighter than air craft, comprising a gas inflated body portion and a tail portion connected to the body portion, said tail portion being adapted to be inflated when the craft is in use, to form a continuation of stream lines of the body portion and being also adapted to be deflated when the craft is not in use, whereby the over-all dimensions of the craft may be materially reduced, without deflating the body portion of the gas bag, to accommodate the craft to housing in a space of less length than the normal length of the craft in flight.
- 15 3. A gas bag for lighter-than-air craft, comprising a normally inflated body portion, and an independently collapsible tail portion connected to the end of said body portion to form a continuation of the lines of said body portion, and having its interior separate and sealed against communication with the interior of said body portion, and means whereby the tail portion may be inflated or deflated independently of said body portion.
- 20 4. A gas bag for lighter-than-air craft,
- 25
- 30
- 35

comprising a normally inflated stream-line body portion, and an independently collapsible tail portion connected to the end of said body portion and forming, when inflated, a continuation of the stream lines of said body portion, said tail portion lying wholly outside said body portion and being inflatable and deflatable independently of said body portion.

5. The combination of a dirigible gas-bag body of stream line form, and a collapsible tail secured to the end of said body and out of communication therewith, the lines of said tail forming a continuation of the stream lines of said body, a valve in said tail whereby said tail may be inflated and deflated independently of said body portion.

6. The combination of a dirigible gas-bag body, of stream line form and closed at both ends, a collapsible tail secured to the rear end of said body, said tail being entirely outside said body and out of communication therewith, the lines of said tail forming a continuation of the stream lines of said body, and a valve in said tail whereby said tail may be inflated and deflated independently of said body portion.

In witness whereof I have signed my name in the presence of two subscribing witnesses.

R. A. D. PRESTON.
